BARREL AND BARREL HEAD THEREFOR

Harry Guthrie Bell, Paris, Ky., assignor to Gay-Bell Corporation, Paris, Ky., a corporation of Kentucky

Application May 24, 1955, Serial No. 510,610

1 Claim. (Cl. 217—44)

This invention resides in the provision of an improved barrel and barrel head therefor and while it will be described as having particular application to tobacco hogsheads and the like it must be understood that such invention has general application in the field of barrels and like containers.

This invention has, for example, particular application to barrels and tobacco hogsheads such as shown in Patent No. 2,454,267 in the name of Harry Guthrie Bell and Jacob Douglas Gay, Jr.; Patent No. 2,470,459 in the name of Harry G. Bell; Patent No. 2,554,357 in the name of Harry G. Bell; Patent No. 2,555,530 in the name of Harry G. Bell and Jacob D. Gay, Jr.; and Patent No. 2,556,789 in the name of Harry G. Bell and Jacob D. Gay, Jr. The barrels and tobacco hogsheads shown in the aforementioned patents have proved quite successful and have admirably fulfilled the need for a good hogshead which existed in the tobacco industry. The passage of time, however, has emphasized certain conditions in the construction of such hogsheads which can stand improvement.

Accordingly it is an object of this invention to provide an improved barrel and barrel head therefor in which the head for both the top and bottom may be put in place without separating or parting the body sections so to do.

A further object of this invention is to provide means for reinforcing the peripheral edge of the barrel head which will at the same time permit the head to flex when it is being put in place within the barrel body.

Yet another object of this invention is to construct the tobacco hogshead and head in such a way that the head constituting the top closure for the hogshead will remain adjacent the upper ends of the staves defining the hogshead even after the tobacco has dried or cured to such an extent as to leave a space below the top head.

These and other objects of this invention will become apparent to those skilled in the art from the following description and with reference to the accompanying drawings in which like numerals are employed to designate like parts throughout and in which:

Figure 1 is a plan view of a barrel or tobacco hogshead to which this invention applies, such barrel or hogshead being shown in assembled condition but without a top or bottom head,

Figure 2 is a side elevation of the hogshead or barrel of Fig. 1,

Figure 3 is a section taken on the line 3—3 of Figure 1,

Figure 4 is a plan view of a barrel head which may constitute the top or bottom head of a barrel or tobacco hogshead,

Figure 5 is a section taken on the line 5—5 of Figure 1,

Figure 6 is a section taken on the line 6—6 of Figure 5,

Figure 7 is an enlarged perspective view emphasizing the construction shown in Figure 6,

Figure 8 is a section taken on the line 8—8 of Figure 4,

Figure 9 is a fragmentary exploded view, in section,

2

showing the bottom head as it is being placed within a barrel or hogshead.

Figure 10 is a perspective view, partly in section, showing the top head being placed within the barrel or hogshead,

Figure 11 is a section taken on the line 11—11 of Figure 10,

Figure 12 is a fragmentary sectional view showing the top head in place within the hogshead right after same has been filled with tobacco, and

Figure 13 is a fragmentary sectional view showing the top head in place within the hogshead after the tobacco therein has cured and settled somewhat.

Referring now to the drawings and especially to Figures 1, 2 and 5, the hogshead has been generally indicated at 20. This hogshead is made up of a plurality of staves 21 which are maintained by intermediate hoops 22 and combination hoops and liners 23, these latter being located at the extreme ends of the staves. The staves 21 are normally made from plywood while the hoops and 15 hoops and liners 22 and 23 respectively are formed of metal. In the Bell et al. Patent 2,555,530 aforementioned these hogsheads are made by taking sheets of plywood, clamping the hoops and hoops and liners in place, stapling 20 these hoops and liners in desired manner and then sawing through the plywood between hoops while grooving the plywood beneath the hoops in order to define a hogshead made up of a plurality of staves. The plywood section or sections as the case may be define the eventual 25 diameter and height of the hogshead. The ends of the hoops and hoops and liners are provided with members 24 to receive pintles 25 in order to secure the section or sections together. The instant invention is not limited 30 in its application to barrels or hogsheads formed in the general manner just described although this has proved 35 to be a good way of constructing articles of this type.

The combination hoop and liner 23 employed at the 40 respective ends of the hogshead are so formed as to provide, see especially Figures 1 and 5, an uninterrupted band of metal 26 about the outer periphery of the staves 21 adjacent their ends, a plurality of metal segments 27 disposed across the ends of each stave 21 with a slight space between segments and corresponding to the lines of 45 cut defining the individual staves, a plurality of flanges 28 sloping downwardly and inwardly from the segments 27, and a plurality of segments 29 each lying substantially across a stave 21 near its end. The metal 30 extending from the end of the flange 28 to the segment 29 lies in a 50 plane which is perpendicular to that of the stave 21.

The hoop and liner members 23 are secured to the 55 hogshead 20 by means of a series of staples 31 which pass through the bands 26, staves 21 and segments 29. The crowns of the staples 31 lie flush against the band 26 while the legs of the staple extend through the stave 21 and band 29 in such a manner that the leg ends or 60 points 32 take the position thus shown in Figures 6 and 7. Special anvils have been constructed to insure that the staple takes the position herein illustrated. This 65 arrangement is quite important to the improved hogshead and head therefor as will be emphasized shortly. In this connection it should be noted that the staple is so formed and clinched that the leg portions 32 do not lie flat against the segment 29 nor do they extend back into the stave 21. Rather these staple end portions 32 pass completely through the segment 29 and are then 70 return-bent so as to engage it thus leaving a slight space 33 between the segment 29 and leg portions 32. This has been shown in exaggerated form in Figure 7 for purposes of illustration. It is necessary to the construction and carrying out of this invention that the staple 31 is

so driven and set as to provide the extending portions 32 in the manner just described.

Referring now to Figures 4 and 8 there is illustrated a head for the barrel or hogshead of this invention. This head 34 comprises a circular disc which may also be made of plywood. A U-shaped band 35 is disposed about the peripheral edge of the head 34 and to this end one end of the band may be tacked in place as indicated at 36 and the band then brought into engagement about the full periphery of the head after which it may be stapled into place as indicated at 37. The legs 38 and 39 of the U-shaped band 35 lie flat against the surfaces of the head 34. No upturned flanges from the members 38 and 39 are utilized. It is preferred that the band 35 about each hogshead head 34 be a single channel member as indicated in Figure 4.

The formation and position of the flange 28 with its perpendicular underportion 30 of the hoop and liner 23, the location and formation of the staples 31, the arrangement of the channel member 35 and the location of the staples 37 act together to produce the improved barrel and barrelhead therefor constituting this invention. This is perhaps best illustrated in Figures 9 through 13.

In erecting the hogshead of this invention a flat section or sections each comprised of the staves 21, hoops 22 and hoop and liners 23 are stood upon the edge 27 of the hoop and liner 23 and physically manipulated to a generally circular form when viewed in plan and the pintles 25 put in place thus maintaining the hogshead in erected condition. The next step is to place one of the heads 34 in the bottom of the barrel or hogshead 20. One way of doing this has been illustrated in Figure 9 wherein a head 34 has been inserted from the top and, as indicated by the arrow, is being moved towards the bottom. It will be a simple matter to wiggle the barrel head 34 past the ends of the staples 32 until it has been brought to rest on the underside 30 of the flange 28, this underside 30 lying in a plane perpendicular to the staves 21. Since there are no upstanding or reinforcing flanges on the U-shaped channel member 35 disposed about the periphery of the head 34 such head may be flexed a bit if necessary in order to get it past the ends of the staples 32. This is one of the reasons for forming the head in this manner. This is perhaps better illustrated in connection with the placing of the top as will be discussed in connection with Figure 10.

When the head 34 has been properly positioned in the bottom of the hogshead the relationship among the various parts will be as shown in Figure 11. The head 34 will rest on the flat portion 30 of the flange 28. The staple 31 is positioned not only so that it will engage the flanges 26 and 29 of the hoop and liner 23 but also so that the distance between the ends 32 and the flat portion 30 just mentioned will be substantially equal to the thickness of the head 34 and the flanges 38 and 39 of the channel member 35. In this manner the head 34 is held snugly in place between the staple legs 32 and flat flange portion 30. In addition the staple 37 is so positioned that it will engage the juncture of flange portions 28 and 30 which gives added rigidity to the construction. In large barrels and hogsheads of the type herein under consideration, wherein it is common for such hogsheads to contain upwards of a thousand pounds of tobacco, it is important that every step be taken to insure the strongest possible construction since these barrels are often subjected to rather rough treatment in handling and during transportation. It is particularly important that the barrel ends be protected against damage since they will often strike other objects while being moved and since they are often dropped thereon. By arranging the flange 28 so as to present the perpendicular portion 30 added rigidity is given to

the ends of the staves 21 and therefore to the end of the hogshead. The position of the staple 37 increases this rigidity as it provides an abutment for the flange members 28 and 30.

After one of the heads 34 has been disposed in the bottom of the barrel or hogshead, such barrel or hogshead is then filled with material which for purposes of illustration has been generally designated at 40 and will be considered as being tobacco. This tobacco will normally be packed into the hogshead under considerable pressure. When it has been loaded with the desired amount of tobacco it then becomes necessary to insert another head 34 on top of the tobacco. In Figure 10 there has been more or less diagrammatically illustrated a manner in which such head 34 may be placed. This figure emphasizes the importance in having the head 34 somewhat flexible as is permitted by the simple channel member 35 disposed about its peripheral edge. An operator may place the head 34 on top of the tobacco and then while standing thereon wiggle it into place with the help of a simple tool or the like as indicated at 41.

After the operator has succeeded in placing the head 34 it will be in the position illustrated in Figure 12. As described in connection with the bottom member so also will this top head 34 be engaged between the flat portion 30 of the flange 28 and the ends 32 of the staples 31. The pressure of the packed tobacco will force the head back over the staple ends 32 and against the flange portion 30. As will be described shortly this has a particular significance in connection with the top member.

As perhaps best seen in Figure 13 the head 34 will be maintained between the staple ends 32 and the flat portion 30 of the flange 28. Again the juncture of flange portions 28 and 30, as indicated at 28a, will abut the staples 37 which hold the flanges 38 and 39 of the channel member 35 in position about the periphery of the head 34.

In addition to the advantages of the construction as described in connection with the bottom member of Figures 9 and 11 it should be observed that there is another important advantage as illustrated in Figures 12 and 13. Figure 12 shows the hogshead right after it has been loaded with tobacco and right after the head 34 has been put in place. With the passage of time, however, the tobacco will shrink somewhat and leave a space beneath the head 34. Were it not for the position and configuration of the staple ends 32 the head 34 would move downwardly within the hogshead upon shrinkage of the tobacco. This would result in removal of support near the ends of the staves 21. Upon rough handling of the hogshead such staves would be much more apt to break if the head 34 were not maintained in the position shown in Figure 13. Thus it is quite important that the staples 31 be positioned so as to have the ends 32 thereof spaced from the flange portion 30 in a manner just nicely to maintain the head 34 therebetween.

Also, as above mentioned, it is important that the staples 37 be positioned so as to engage the juncture 28a of the flange portions 28 and 30 when in position. This may be emphasized by noting that the flanges 28 extend from the uppermost flange 38 and staples 37 of the head 34 to the segments 27 located on the tips of the staves 21. While the periphery of the head 34 will itself support the staves 21 near their ends, support for the very ends or tips of such staves is derived from this flange 28. By having the flange 28 braced against the staples 37 such support for the stave tips is much enlarged.

All these and other advantages will be apparent to those skilled in the art. It is to be understood, however, that modifications may be made in the construction of the improved barrel and barrel head of this invention without departing from its scope and spirit. It is to be further understood that while this invention has been shown as embodied in certain particular arrangements and struc-

tures, the invention is not to be limited to such arrangements and structures except insofar as they are specifically set forth in the subjoined claim.

The invention having been thus described, what is claimed as new and what is desired to be protected by United States Letters Patent is:

An improved barrel and barrel head comprising: a first reinforcing member disposed about the edge of said barrel, said member comprising an uninterrupted band disposed flat about the outside of said barrel, a plurality of first segments extending from said band and disposed about the extreme edge of said barrel, a plurality of flanges sloping inwardly from said first segments, flange portions extending outwardly from the innermost ends of said flanges to the inside of said barrel and perpendicular thereto, and second segments extending downwardly from said flange portions and perpendicular to said flange portions, said second segments being disposed flat about the inside of said barrel; a second reinforcing member disposed about the periphery of said barrel head, said last mentioned member comprising a U-shaped channel member having the bridge of the U engaging the extreme edge of said head and the legs of the U being disposed flat about either side of the head; first U-shaped staples passing through said band and said second segments, the

5

10

15

20

25

inner end portions of said first U-shaped staples being return-bent and projecting inwardly of the inner surface of said second segments and presenting first abutments spaced from said second segments inwardly of said barrel; second U-shaped staples passing through the legs of said U-shaped member parallel to said second segments and presenting second abutments on the outer side of said head; said first U-shaped staples being parallel to said flange portions and spaced from said flange portions a distance slightly greater than the thickness of said head and said second reinforcing member whereby said first abutments hold said head immediately adjacent said flange portions; and said second abutments being spaced from the edge of said head so as to engage the innermost ends of said flanges when said head is in place within the barrel and engaged between said first abutments and said flange portions.
